UNITED STATES PATENT OFFICE.

EDWARD J. SONNENBURG, OF WATTS, CALIFORNIA.

LOOSE-SHEET BINDER.

Application filed January 10, 1921. Serial No. 436,140.

To all whom it may concern:

Be it known that I, EDWARD J. SONNENBURG, a citizen of the United States, residing in Watts, in the county of Los Angeles and State of California, have invented a new and useful Loose-Sheet Binder, of which the following is a specification.

My invention relates to the art of book binding, being more particularly a binder 10 for holding loose folded sheets such as sheet music and the like.

The principal object of my invention is to provide a binder of the class described of simple form and construction in which 15 sheets may be readily bound and easily removed.

Other objects will appear from the following description and drawings.

Referring to the drawings which are for 20 illustration purposes,

Fig. 1 is a face view of a binder embodying a form of my invention showing a folded sheet in place, one leaf of the sheet being broken away,

25 Fig. 2 is a cross sectional view on a larger scale on line 2-2 Fig. 1.

Fig. 3 is an enlarged sectional view on line 3-3 Fig. 1.

Fig. 4 is a fragmentary perspective view 30 showing a portion of single sheet and binding rod.

Fig. 5 is a cross sectional view of a portion of a binder showing a modified form of construction, and Fig. 6 is a similar view 35 of a modified form of staple.

11 designates the back of the binder made of wood or other suitable stiff material covered with a flexible covering material 12, to which is attached in the ordinary manner 40 the front cover 13 and the back cover 14. Attached to the top and bottom of the back 11 in any suitable manner as by nails 15 are plates 16 forming retaining means for certain rods hereinafter referred to.

45 Secured to the back on the inside of the binder are two staples 18, the points 19 of the staples extending into the back 11 and the central part or bridge of the staples being spaced apart from the face of the back 11. 20, 20 designate rods arranged 50 to extend under the staples 18 for the purpose of retaining the sheets designated at 21 in the binder. Secured to the inside of the back cover 14 is an envelope or container 22 for holding the rods 20 when not in use.

The binder is used in the following manner; the folded sheet to be placed in the binder, in the form shown a music sheet is cut out or notched at the folding line 23 60 as indicated at 24 such notches being spaced apart to correspond with the staples 18. The folded portion of the sheet is then placed in the binder as shown in Fig. 1 the staples extending through the notches in 65 the sheet. When in this position a rod 20 is run under the staples along the folding line of the sheet thereby holding the sheet in place in the binder. The rod with the sheet thereon is slideable on the staples thereby 70 permitting adjustment and the insertion and removal of additional sheets to and from the binder.

The retaining plates 16 prevent dislodgment of the rods longitudinally but are not 75 connected mechanically to the rods. A sheet is removed from the binder by raising one end of the rod holding the sheet above the plate 16 and withdrawing the rod from the staples thereby freeing the sheet.

80 As shown in Fig. 2 the sheets in the binder lie flat being a particularly desirable feature as the entire sheet is exposed except that portion directly under the rod 20.

In Fig. 5 I have shown a modified form 85 of staple indicated at 30, such staple forming substantially a half round, the back 31 having its inner face 32 correspondingly faced.

In Fig. 6 the sides of the back are provided with slots 35 into which the side members 36 of the staple extend, the ends 37 of the staple extending from the sides into the back.

I claim as my invention:

95 1. A loose sheet binder comprising a back, a plurality of uniformly bent staples fixed at both ends to said back having their central portion spaced apart from the back, arranged to extend through notches formed 100 in the sheets, and a loose rod consisting of a straight unbent wire for each sheet extending under the staples.

105 2. A loose sheet binder comprising a back, a plurality of staples fixed to said back arranged to extend through notches formed in the sheets, a loose rod extending under said staples engaging its associated sheet along the folding line thereof, and means secured to the back of the binder beyond 110 the ends of said rods for retaining said rods in said staples.

3. A loose sheet binder comprising a back, uniformly bent members fixed to said back at both ends arranged to extend through notches formed in the folded edge of the sheets, a loose rod for each sheet extending under said staples 15 engaging its associated sheet along the folding line thereof, and a plate at the top and bottom of said back secured thereto and extending inwardly from said back beyond the ends of said rods.

4. A loose sheet binder comprising a back,

In testimony whereof, I have hereunto set my hand at Los Angeles, California, this 28th day of December, 1920.

EDWARD J. SONNENBURG.
